Inventor

By Victor J. Evans Attorney

UNITED STATES PATENT OFFICE.

DEWEY LEE JONES, OF COLUMBUS, GEORGIA.

ROD FINGER.

Application filed March 24, 1924. Serial No. 701,506.

To all whom it may concern:

Be it known that I, DEWEY LEE JONES, a citizen of the United States, residing at Columbus, in the county of Muscogee and State of Georgia, have invented new and useful Improvements in Rod Fingers, of which the following is a specification.

This invention relates to protector mechanism for looms, the general object of the invention being to provide means for preventing injury to the protector rod which carries the binder engaging finger when the dagger engages the frog on the failure of a shuttle to be boxed.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a side elevation of a portion of a loom showing my invention in use.

Figure 2 is an enlarged view of the improved finger.

In these views, A indicates the loom frame, the lay being shown at 1, the shuttle box at 2, the shipper at 3, the knock off lever at 4 and the frog at 5. The spring actuated dagger rod is shown at 6 and the dagger at 7 for engaging the shoulder 8 on the frog when the lay moves forwardly and the shuttle has failed to be boxed. The protector rod is shown at 9 and is connected with the dagger rod and the binder finger shown at 10 and is clamped on the rod 9 by the set screws 11.

My invention comprises in providing the finger with a spring pressed plunger 12 which passes through a hole 13 formed in the upper end of the finger and has its head 14 engaging the binder 16. The spring is shown at 17, and has its ends bearing against the finger and the head, and 14' indicates a lock nut on the outer end of the plunger.

As is well known, when a shuttle fails to

be boxed the spring on the dagger rod will force the dagger downwardly so that it will engage the shoulder 8 on the frog 3 to cause the same to engage the lever 4 and thus stop the loom through well known mechanism. When a loom is properly boxed the binder 16 engaging the finger 10 will prevent the spring on the dagger rod from lowering the dagger into engagement with the shoulder on the frog and thus the loom continues to operate until a shuttle fails to be boxed and the parts come into operation as before described and stop the loom. The sudden check given the lay and its attached parts by the engagement of the dagger with the shoulder frequently causes the arm or rod 9 to bend or break but with the spring plunger on the finger this damage to the rod cannot take place as the plunger will be pressed outwardly, thus permitting a certain amount of movement of the rod 9 and the finger 10 to prevent damage to the rod. As soon as pressure is relieved the plunger is returned to its normal position by its spring.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A binder finger for use upon looms having an enlarged transversely bored lower portion, a protector rod removably secured within the bore and having its opposite end portion connected with the loom mechanism, a plunger member transversely disposed within the upper end of the finger, a compression spring encircling the plunger and arranged between the plunger head and finger, a lock-nut arranged upon the opposite end of the plunger, and a binder arranged adjacent to and resiliently engaging the head of the plunger whereby the loom will continue to operate until a shuttle fails to be boxed.

In testimony whereof I affix my signature.

DEWEY LEE JONES.
